UNITED STATES PATENT OFFICE.

REGINALD L. S. DOGGETT, OF EAST ORANGE, NEW JERSEY.

VARNISH OR COLOR CUP.

SPECIFICATION forming part of Letters Patent No. 748,052, dated December 29, 1903.

Application filed October 14, 1902. Serial No. 127,206. (No model.)

To all whom it may concern:

Be it known that I, REGINALD L. S. DOGGETT, a citizen of the United States, and a resident of East Orange, county of Essex, and 5 State of New Jersey, have invented a new and Improved Varnish or Color Cup, of which the following is a specification, reference being had therein to the accompanying drawings, in which—

10 Figure 1 is a vertical sectional view; Fig. 2, a side elevation showing the handle reversed; Fig. 3, a detail of the reversible handle detached; Fig. 4, a plan view of the main receptacle; Fig. 5, a vertical sectional view 15 showing the strainer attachment in position, and Fig. 6 a detail of the strainer attachment detached.

One of the objects of this invention is to provide simple means for detachably securing together the main receptacle and the wiping-receptacle.

Another object of the invention is to provide for the main receptacle a reversible and vertically-adjustable handle.

25 A further object of the invention is to provide a simple strainer by means of which the varnish and color may be freed from foreign substances, which strainer is designed to be detachably secured to the top of the main receptacle.

Other and equally important objects of the invention will appear hereinafter.

The device is comprised of three receptacles, the main color or varnish holding receptacle 1 being of any desired shape and considerably larger than the supplemental section 2. The main receptacle is preferably formed with a straight portion 3 of its vertical wall, the upper end of this straight portion forming a wiping edge. Opposite this straight portion 3 and to the outer side of the vertical wall of the main receptacle are secured two vertical guides 4, which are parallel and are separated from each other a suitable distance, their upper ends fitting against the lower edge of the flange 5, formed around the upper edge of the receptacle. Fitting between these guides and the outer wall of the receptacle is a plate 6, whose vertical edges are adapted to slide under edges of the guides, said plate being adapted to be removed from engagement with the guides

at the lower ends thereof, the flange at the upper edge of the receptacle preventing the plate being upwardly withdrawn from between them. Secured to the outer side of this slide is a handle 7, which is located nearer to one end of said slide than to the other end thereof. The object of this particular construction is to permit the handle to be adjusted vertically on the receptacle to adapt it to the hand of the person using the color or varnish cup and, further, to permit the handle to be reversed, as shown in Fig. 2, to bring the handle near the upper or lower edge of the receptacle, as may be desired by the person using the cup. When the handle is in the position shown in Fig. 1, it is intended that the thumb of the hand be inserted therein, the bottom of the main receptacle 70 resting on the palm of the hand. In this way the entire weight of the device is supported in the palm of the hand, thereby relieving the fingers of all the strain of supporting the cup. When the handle is in the position shown in Fig. 2, the fingers are inserted through the handle in the usual way. By thus providing a reversible handle the cup 75 may be held by the user in any one of various ways.

80 The supplemental receptacle 2 is formed with the straight inner wall 9, which is of substantially the same height as the vertical wall of the main receptacle, and this inner wall is provided at its upper edge with a downward-extending lip 10, which is adapted to be engaged over the upper edge of the straight portion 3 of the main receptacle. Near the lower edge of this wall 9 is secured a bracket 11, which is adapted to engage keepers or guides 12, secured to the straight portion 3 of the main receptacle near the lower edge thereof. By this means the supplemental receptacle is firmly but detachably held to the main receptacle opposite the handle of said 95 main receptacle. The outer wall of this supplemental receptacle is extended above the inner wall thereof, and consequently above the wall of the main receptacle, when the two receptacles are connected together, and the upper edge of this outer wall is formed into a wiping edge 13. The upper end of this outer wall is turned over to form a smooth edge, which will permit the brush to be drawn

over it without in the least injuring the hair or bristles of the brush. As shown in the drawings, this wiping edge is straight and horizontal; but it is evident that it may be curved to accommodate and preserve the natural shape of the various forms of brushes, the straight wiping edge shown in the drawings being best adapted for flat brushes.

The supplemental receptacle is adapted to receive the wipings from the brush after the brush has been used and before it is dipped into the varnish or color contained in the main receptacle. The object of this is to prevent the dust and all foreign substances which may adhere to the brush while it is in use from entering the varnish in the main receptacle, thereby keeping the varnish or color clean and of a uniform consistency.

To provide a convenient means for straining the wipings or other varnish or color which is to be poured into the main receptacle, a straining attachment is provided. This attachment is comprised of an open-ended tubular section 14, which is of the same horizontal contour as the main receptacle, but slightly smaller in diameter in order that its lower edge may be passed within the said receptacle. Secured to the outer wall of this section 14 are three downward-extending clips or clamps 15, which are adapted to engage over the upper edge of the main receptacle on the outer side thereof to detachably hold the section 14 in position. Clamped between the main receptacle and the lower edge of the section 14 and extending entirely across the main receptacle is a sheet of straining material 16, such as filtering or cheese cloth. It is obvious that it is only necessary to pour the contents of the supplemental receptacle into the section 14 and to agitate it and permit it to flow through the filtering or cheese cloth into the main receptacle. It is obvious that all of the varnish or color may be strained when it is poured into the main receptacle, if desired.

The main receptacle is formed with the vertical wall *a* and the bottom *b*. The bottom is curved upward at its edges, as shown clearly in Fig. 1, the main part of the bottom, however, being flat and forming a resting-surface for the cup. The joint between the upper edge of the bottom piece and the lower edge of the vertical wall is flush on the inner side of the receptacle, a shoulder *c* being formed on the bottom to receive the lower edge of the vertical wall and to maintain the inner surfaces of the bottom section and the vertical wall flush at their meeting edges. The object of this is to avoid all corners and large seams in the interior of the cup, thus rendering it very easy to clean and preventing the lodgment of varnish or color in the same. The bottom of the supplemental or wiping receptacle and the vertical wall thereof is connected in the same manner as the bottom and vertical wall of the main receptacle and for the same purposes.

Having thus described my invention, what I claim as new, and desire to secure by Letters Patent, is—

1. In a varnish and color cup, the combination of a main receptacle formed with an outward-extending flange at its upper edge, a supplemental wiping-receptacle secured to the outer side of the main receptacle, the upper edge of the outer wall of this wiping-receptacle being formed into a brush-wiping edge, a pair of vertical guides secured to the outer side of the main receptacle and extending from the outward-extending flange at the upper edge thereof to a point near the bottom of said receptacle, a vertically-slidable plate having its vertical edges engaged under the guides attached to the receptacle, the upper edge of said plate abutting against the flange at the top of the receptacle when said plate is in its uppermost position and being freely removable from said guides at the lower ends thereof, and a handle secured to said plate nearer to one end than to the other, whereby said plate and handle may be reversed in the guides for the purpose set forth. 75

2. In a varnish and color cup the combination of a main receptacle, a supplemental wiping-receptacle detachably secured to the outer side of the main receptacle, the outer wall of said supplemental receptacle being extended above the wall of the main receptacle, the upper edge of said outer wall being formed into a brush-wiping edge, and the inner wall 100 of said supplemental receptacle being of substantially the same height as the wall of the main receptacle, and a vertically-movable and reversible handle-plate detachably secured to the outer side of the main receptacle, and a handle secured to said plate nearer to one end thereof than to the other, whereby in one position of the plate the handle will be near the top of the receptacle, and in its reverse position it will be near the bottom 110 thereof. 95

3. In a varnish and color cup the combination of a main receptacle, a wiping-receptacle detachably secured to the outer side of said main receptacle, the outer wall of said supplemental receptacle being extended above the top of the main receptacle, the upper edge of said outer wall being formed into a wiping edge, and the inner wall of said supplemental receptacle being of substantially 115 the same height as the wall of the main receptacle, a vertically-movable and reversible slide secured to the outer side of the main receptacle at a point opposite the wiping-receptacle, and a handle secured to said slide 125 nearer to one end thereof than to the other, whereby in one position of the plate the handle will be near the top of the receptacle, and in its reversed position it will be near the bottom thereof. 130

4. In a varnish and color cup the combination of a main receptacle formed with one straight vertical wall, a supplemental wiping-receptacle provided with clips by which it

may be detachably connected to the straight vertical wall of the main receptacle, one of said clips fitting over the upper edge of the straight vertical wall of the main receptacle, the outer wall of said supplemental receptacle extending above the main receptacle, the upper edge of said outer wall being formed into a wiping edge, a reversible and vertically-movable slide secured to the outer side of the main receptacle at a point opposite the straight wall thereof, and a handle secured to said slide nearer to one end thereof than to the other end, substantially as described, whereby in one position of the plate the handle will be near the top of the receptacle, and in its reversed position it will be near the bottom thereof.

5. In a varnish and color cup, the combination of a main receptacle, a supplemental wiping-receptacle detachably secured to the outer side of the main receptacle, the outer wall of said supplemental wiping-receptacle being extended above the wall of the main receptacle, the upper edge of said outer wall 25 being formed into a brush-wiping edge and the inner wall of said receptacle being of substantially the same height as the adjacent

wall of the main receptacle, clips connected to the supplemental receptacle and engaging the adjacent wall of the main receptacle, a pair of guides secured to the main receptacle at a point substantially opposite the supplemental receptacle and extending from the upper edge thereof to a point near its bottom, a vertically-slidable plate held between these guides, means at the upper end of the guides for preventing said plate being upwardly withdrawn therefrom, said plate being freely removable from said guides at the lower end thereof, and a handle secured to said plate nearer to one end thereof than to the other, whereby in one position of the plate the handle will be near the top of the receptacle and in its reversed position the handle will be near the bottom of said receptacle.

In testimony whereof I hereunto affix my signature, in the presence of two witnesses, this 13th day of October, 1902.
